UNITED STATES PATENT OFFICE

ARTHUR A. BYERLEIN, OF DETROIT, MICHIGAN, ASSIGNOR, BY MESNE ASSIGNMENTS, TO GENERAL MACHINERY CORPORATION, OF HAMILTON, OHIO, A CORPORATION OF DELAWARE

PRESS

Application filed March 27, 1929. Serial No. 350,310.

This invention relates to presses, and more particularly to presses having a movable slide which is adjustably connected to the means which operates it.

5 One object of the invention is the provision of a press of this character having a member or members adjustably supported on the die slide and pivotally connected to angularly moving arm or toggle link operating means, 10 the upper end of the adjustable member being guided in a part which is attached to the slide so that bending forces applied to the member are taken by the slide.

15 Other objects and advantages of the invention will be apparent from the following description and from the accompanying drawings, in which—

Fig. 1 is a central transverse vertical section through a portion of a press embodying 20 the present invention; and

Fig. 2 is a horizontal section on the line 2—2 of Fig. 1.

Referring to the embodiment of the invention illustrated in the drawings, 10 designates the frame of a press, only a portion of this frame being shown as it may have any suitable form well known in the art. Guided for reciprocatory movement in the frame 10 are the plunger 11 and the blank holder 12, the former being connected by a suitable crank connection 13 to the crank shaft 14, while the blank holder is operated by a system of toggle links from a pair of toggle shafts 15, one of which is provided on opposite sides of the press in accordance with the usual practice. Fixed to the rock shaft 15 is a toggle arm 16 which is pivotally connected to the upper end of the toggle link 17. The lower 40 end of the toggle link 17 is provided with a pin 20 which extends through the flattened lower end thereof and which is rotatably journaled in suitable bearing portions 21 in the bifurcated connection member 22. This connection member 22 forms the upper end of an adjusting member or threaded rod 24 which extends through a lug 25 provided on the side of the slide 12. Suitable adjusting and positioning nuts 26 and 27 are threaded 50 on the rod 24 and cooperate with the upper

and lower surfaces of the lug 25 to adjustably fix the rod 24 relatively to the slide 12.

The slide projections 25 are preferably provided adjacent the four corners of the slide 12, extending forwardly and rearwardly therefrom as shown. Each corner of the slide is similarly constructed and the four sets of toggle links provided on the two rock shafts 15 cause vertical reciprocatory movement of the slide 12 which is preferably actuated with 60 a dwell in its movement so as to serve as a blank holder for sheet metal or the like and cooperate with the plunger or stamping slide 11.

The provision of the adjustment of the 65 relative setting of the rods 24 on the blank holder 12 permits variation of the upper and lower limits of travel of the blank holder to compensate for dies of various depths.

It has been found that in prior constructions of this general nature considerable side pressure is applied to the threaded adjusting members on the slide as they are moved downwardly or raised by angularly movable toggle arms. The upper ends of the threaded members must project some distance above the projections on the slide to which they are attached and the threaded members must either be made very large to take care of bending forces applied to them or else they are liable to fracture due to the pressures exerted at an angle to their longitudinal axes. Attempts have been made to remedy this condition in the past by interconnecting adjacent adjusting members but this merely serves to transfer a bending force from one adjusting member to another without transmitting the bending force to the slide or some other large and rigid part which is adapted to 80 assume it.

In accordance with the present invention the upper end of the various adjusting members 24, where they are connected to the lower ends of the toggle links 17, are so received in guide members fixed to the slide that bending strains applied to the threaded bolts or adjusting members is transferred directly and immediately to the slide. The upper ends of the various adjusting members 24 are positioned against lateral movement in any 10

direction. The connecting members 22 at the upper ends of the threaded bolts 24 are guided for vertical movement freely within collars 30 which are fixed to the upper portion 5 of the slide 12, preferably by means of bolts 31 or the like so that they may be readily fastened in place or removed. Each connecting member 22 is provided with a comparatively long preferably cylindrical bearing 10 surface 32 which is received with a sliding fit in a bore provided in the collar 30. The vertical height of the collar is preferably considerably less than the vertical extent of the bearing surface 32 on the connecting member 15 22 so that the latter may be moved up and down within the fixed collar 30 as the nuts 26 and 27 are adjusted and as the adjusting rod 24 is set to new positions in the slide. The fit between the bearing surface 20 32 on the connecting member 22 and the bearing surface in the collar 30, while permitting free relative movement in a vertical direction, prevents any bending force exerted on adjusting member 24 from straining or bending 25 the bolt, as such bending forces are immediately applied to the collar 30 which is fixed to the slide. All such bending forces are therefore immediately transferred to the slide and the adjusting members 24 are not 30 injured. The collars or guides 30 are effective in the various positions of adjustment 35 of the threaded adjusting members 24, and the latter are engaged at the upper ends thereof and directly adjacent the points of application of force to the adjusting members. Those thrusts which would otherwise be likely to bend the threaded bolt just above the adjusting nut 26 are therefore transmitted to the slide and have no bending effect on 40 the bolts. By reason of the construction herein set forth the various parts may be made considerably lighter while obtaining a strong and rigid construction.

While the form of apparatus herein described 45 constitutes a preferred embodiment of the invention, it is to be understood that the invention is not limited to this precise form of apparatus, and that changes may be made therein without departing from the 50 scope of the invention which is defined in the appended claims:

What is claimed is:

1. In a toggle press, a frame, a slide operable in said frame, a toggle link for operating said slide, a member adjustably supported on said slide and pivotally connected to said link, and a guide fixed to the slide and guiding an upper portion of said member to receive and withstand horizontal components of the 60 thrust of said link when the link is inclined.
2. In a press, a frame, a slide operable in said frame, an angularly movable link for operating said slide, a member adjustably fixed to said slide and pivotally connected to said link, and a guide fixed to said slide and

slidably receiving the upper end of said member.

3. In a toggle press, a frame, a slide operable in said frame with a dwell in its movements, a toggle link for operating said slide, a threaded member adjustably supported on said slide, adjusting nuts for adjusting said member relatively to said slide, a pivotal connection between the upper end of said threaded member and said link, and a guide fixed to the slide above said adjusting nuts, said guide slidably receiving the upper end of said threaded member. 70

4. In a press, a frame, a slide operable in said frame, an angularly movable link for operating said slide, a threaded member adjustably fixed to said slide, a pivotal connection between the upper end of said threaded member and said link, the upper end of said threaded member having a substantially cylindrical bearing surface, a collar fixed to said slide adjacent the upper end of said threaded member and having a cylindrical bore slidably receiving said bearing surface, the vertical extent of said bearing surface 80 being much larger than the height of said collar so that bending strains applied to said threaded member are transmitted to the slide by said collar in the various positions of adjustment of said threaded member. 85

5. In a toggle press, a frame, a slide operable in said frame with a dwell in its movements, a series of toggle links for operating said slide, threaded members adjustably supported on said slide adjacent the corners 100 thereof; pivotal connections between the upper ends of said threaded members and the lower ends of said links, and a guide for the upper end of each threaded member, said guides being fixed directly to the slide adjacent the corners thereof and slidably receiving the upper portions of said threaded members. 105

In testimony whereof I hereto affix my signature.

ARTHUR A. BYERLEIN.
